UNITED STATES PATENT OFFICE

2,482,639

ELEVATOR SHAFT DOOR

Julius A. Schweig, Clayton, Mo., assignor to Security Fire Door Company, St. Louis, Mo., a corporation of Missouri

Application March 27, 1947, Serial No. 737,582

1 Claim. (Cl. 292—40)

This invention relates to elevator shaft doors of the kind wherein two vertically sliding, counterbalanced door sections move in opposite directions in opening and closing in unison, and the lower door section is provided with a latching device which prevents joint opening movement of both door sections, but does not prevent the upper door section from being opened independently of the lower door section. The present invention has for its principal objects to provide a separate latching device for the upper door section; to provide means controlled by the movement of the lower door latch to operative position for moving the upper door latch to operative position; to provide for moving the upper door latch to inoperative position when the lower door latch is moved to inoperative position; and to provide for simplicity and cheapness of construction and compactness of design.

The invention consists in the elevator shaft door construction and in the parts and combinations and arrangements of parts hereinafter described and claimed.

In the accompanying drawings, which form part of this specification, and wherein like symbols refer to like parts wherever they occur.

Fig. 1 is a shaft side elevational view of an elevator shaft door construction embodying my invention.

Fig. 2 is an enlarged fragmentary shaft side elevational view in the region of the locking device,

Fig. 3 is a side edge elevational view of the parts shown in Fig. 2; and

Fig. 4 is a horizontal sectional view on the line 4—4 in Fig. 2.

In the accompanying drawings, my invention is shown embodied in a vertically sliding, center-parting, counterbalanced door construction of the kind used for closing the door space or opening in an elevator shaft. Said door construction comprises vertical sliding upper and lower door sections 1 and 2, respectively, each provided along each vertical edge with an angle bar side rail 3 having an outstanding flange slidably arranged between an upright double angle bar door guide 4 rigidly secured to the adjacent jamb member 5 of the door frame. A guide shoe 6 is fixed to the outstanding flange of the angle bar side rail 3 and straddles one flange of the double angle bar door guide 4.

The upper and lower door sections 1 and 2 are counterbalanced by means of chains 7 that are connected, as at 8, to the lower corners of the upper door section. The chains 7 extend

upwardly around sheaves 9 mounted on the angle bar door guides 4 and thence downwardly in the direction of the lower door section 2 where they are connected to the upper ends of upright chain rods 10 whose lower ends are secured to the outer ends of door arms 11 that project horizontally beyond the side edges of said lower door section. By this arrangement, each door section acts as a counterbalance for the other door section, whereby the door may be easily opened by pushing down on the lower door section 2 or by pushing up on the upper door section 1.

The lower door section 2 is provided with a latching device comprising an operating lever 12, which is pivotally mounted on the shaft side of the said door section 1, and oppositely extending horizontal latch bars 13 pivotally connected at their inner ends to the respective upper and lower arms of said operating lever. The latch bars 13 are supported on the lower door section 2 for horizontal sliding movement into and out of engagement with suitable keepers 14 or interlocks (not shown) fixed to the double angle bar door guides 4. A coil spring 15 is attached at one end to one of the arms of the lever 12 and at its other end to a lug 16 on the lower door section 2, the parts being arranged so that the spring tends to project the latch bars into latching position.

From the construction thus far described, it will be seen that the latching device on the lower door section prevents both door sections from opening in unison; but said latching device does not prevent the upper door section from being opened independently of the locked lower door section by lifting the dead weight of the upper door section. In order to prevent the upper door section from being separately opened when both sections are locked against joint opening movement, the upper door section is provided with a separate latching mechanism that will positively lock the closed upper door section when the closed lower door section is locked and will unlock said closed upper door section when said closed lower door section is unlocked.

The separate latching device for the upper door section comprises a latch bolt 17 that is supported for axial sliding movement in a holder plate 18 that is mounted on a main or base plate 19 secured flatwise by means of bolts to the outstanding flange of one or each of the double angle bar door guides 4. The latch bolt 17 is slideable crosswise of the double angle bar door guide 4 and is adapted, in the closed position of the upper door section, to move across the top of the guide shoe

6 fixed to the adjacent angle bar side rail 3 of said upper door section.

The latch bolt 17 is moved into and out of locking position by means of an upright lever 20 that is pivotally supported, as at 21, on a bracket 22 fixed to the main or base plate 19. The latch bolt holder 18 and the lever supporting bracket 22 are secured to the base plate 19 by means of bolts 23 which also secure said base plate to the outstanding flange of the double angle bar side rail 4. The lever supporting pivot 21 is disposed horizontally and at right angles to the latch bolt 17, whereby the lever 20 is adapted for vertical swinging movement in the direction of the sliding movement of said latch bolt. The upper arm of the lever 20 terminates in a bifurcated or forked end portion 24 that straddles the transversely grooved portion of the latch bolt 17; and the lower arm of said lever has an abutment stud 25 threaded therethrough with one end in abutting relation to the effective end of the adjacent spring projected latch bar 13 of the closed lower door section. A coil compression spring 26 is interposed between the upper, latch bolt engaging arm of the lever 20 and the base plate 19 and has one end supported on a lug 27 on said arm and the other end supported on a lug 28 on said plate.

When the door is closed, the latch bar 13 of the lower door section in moving upwardly from the dotted position shown in Fig. 2 snaps over the upper end of said keeper 14 on the door guide 4, thus locking the lower door section in closed position. At the same time, the outer or effective end of the latch bar 13 bears against the end of the abutment stud 25 on the lower arm of the lever 20, thus swinging the same in a direction that will slide the effective end of the latch bolt 17 across the top of the guide shoe 6 fixed to the closed upper door section, whereby said end of said latch bolt serves as a stop for said guide shoe and thus prevents said upper door section from being opened. When the latching mechanism for the lower door section is operated to retract the latch bar 13 and thus unlock said section, the endwise pressure of said latch bar on the abutment stud 25 at the lower end of the lower arm of the lever 20 is relieved, thus permitting the coil compression spring 26 to swing said lever in a direction that will retract the latch bolt 17 for the upper door section and thus permit the latter to be opened. Thus, the upper door latching mechanism is moved to locking position by the movement of the lower door latching mechanism to locking position and is moved to unlocking po-

sition when said lower door latching mechanism is moved to unlocking position. The length of movement of the latch bolt 17 may be regulated by adjusting the threaded abutment stud 25 in the lever 20.

Obviously, the hereinbefore described elevator shaft door construction admits of considerable modification without departing from the invention. Therefore, I do not wish to be limited to the precise arrangements shown and described.

What I claim is:

In a door construction comprising a door frame, slideable upper and lower door sections movable vertically in unison in opposite directions to open and close said frame and a latch bar mounted on the lower door section for horizontal sliding movement into and out of locking engagement with said door frame in the closed position of said lower door section, the combination of separate means for locking said upper door section in closed position, said upper door section locking means comprising a latch bolt mounted on said door frame for horizontal sliding movement into and out of locking relation to said upper door section in the closed position thereof, an upright lever mounted on said frame with its upper end directly connected to said latch bolt for moving the same into and out of locking position, a stud carried by the lower end of said lever and positioned to be engaged by the effective end of said latch bar in the locking position thereof to move said lever in a direction that will move the latch bolt connected to the upper end thereof to locking position, said stud being adjustable relative to said lever for varying the length of movement of said latch bolt, and a spring interposed between said frame and said lever for holding said stud in abutting engagement with said effective end of said latch bar in all positions thereof and for moving said lever in a direction that will move said latch bolt to unlocking position when said latch bar is moved to unlocking position.

JULIUS A. SCHWEIG.
